FOUNTAIN PEN FILLING DEVICE

George W. Oakes, Crystal City, Mo.

Application January 30, 1946, Serial No. 644,305

2 Claims. (Cl. 226—63)

1

This invention relates to a device which may be used in conjunction with a font for filling an article with suitable fluid or liquid.

The device may be applied to a commercial ink bottle and receive the writing end of a fountain pen for the purpose of filling the pen with ink, said device being of the type disclosed in my United States Patent No. 2,424,896.

The principal object of the present invention is the provision of a device of the indicated character embodying improvements whereby filling operations may be carried out quicker and easier.

With the foregoing, other objects of the invention will appear when the following specification is read in conjunction with the accompanying drawing, in which

Fig. 1 is a sectional view showing the device of the present invention in use.

Fig. 2 is a sectional view showing the device in an upright position at rest but ready for use.

Fig. 3 is a sectional view taken on the line 3—3 of Fig. 2 and looking in the direction indicated by the arrows.

Fig. 4 shows the keeper of the valve detached.

The device as shown in the drawing includes a body 10 made wholly of resilient material such as rubber. The body 10 is constructed to provide compressible and expandable means at one end and adapted when manipulated to receive a quantity of fluid or liquid and to discharge it therefrom. Said means in the present instance consists of a bulb 11. The body 10 as formed provides a tubular portion constituting an outlet means 12 adapted to receive a portion of an article to be filled with fluid. Since the body is made of resilient material the outlet means 12 is in the nature of an expandable and contractible socket or nipple into which an article to be filled may be projected regardless of the cross sectional size within certain limits. A throat 13 formed in the body 10 provides a restricted passage 14 to control the flow of fluid from the interior of the bulb 11 to the passage provided by the outlet means 12, subject to the manipulation of the bulb.

The features hereinabove described are embodied in the device disclosed in my United States Patent No. 2,424,896.

In accordance with the present invention, the body 10 is formed to provide an inlet end 15 on the bulb 11 in axial alignment with the outlet means 12. The inlet end 15 has a flange 16 which accommodates a circular adaptor 17. The flange 16 is disposed inside of the adaptor 17

and serves as a resilient gasket. The adaptor has means such as a thread 18 for the purpose of attaching the device to a container supplied with fluid or liquid. The inlet end 15 has connected therewith valve means to control the flow of fluid between said container and the bulb 11. The valve means cooperates with the bulb to increase the flow of fluid toward the outlet during the pressure period, and also when the pressure is withdrawn from the bulb, by creating a partial vacuum in the article to be filled while projecting into the outlet means.

The aforesaid valve means may be diversely formulated. In the present instance, said means 15 consists of a sleeve or tubular member 19, a valve member 20, and a keeper 21. These parts are made of acid resistant materials. The sleeve 19 and keeper 21 are made of plastic material. The valve member 20 is globular and is made of glass or the like. The sleeve 19 has an inwardly directed flange 22 on the inner end, and an outwardly directed flange 23 on the outer end thereof. The flange 22 constitutes a seat for the valve member 20 which is freely movable in the sleeve 25 19 between a closed position on the seat and an open position. The keeper 21 is arcuate and has laterally inwardly directed projections 24. Because the keeper 21 is made of resilient material, the keeper may be flexed to enable the 30 projections 24 to be snapped under the flange 23, and between it and the gasket 16. Thus the keeper 21 is securely held in place, yet it may be removed for the purpose of inserting the valve member 20. The keeper 21 limits the opening 35 movement of the valve member or ball 20 to a position in which fluid may pass into the bulb 11 through the sleeve 19. The flange 22 has a notch 25 therein which provides a vent for a purpose to be explained.

40 The device may be used advantageously for filling a fountain pen with ink from a suitable container supplied with such fluid. In Figs. 1 and 2 there is shown a container in the form of a bottle 26 and a fountain pen 27. The adaptor 45 17 is screwed on the outlet neck of the bottle. The writing end of the pen is inserted into the outlet means 12. If desired, a suitable clamp 28 may be used to securely connect the device with the pen.

50 To fill the pen the bottle with the device and pen interconnected, as explained, is grasped with one hand and held in an inverted position, as shown in Fig. 1. This causes some ink to flow from the bottle into the bulb before the valve member or ball 20 can drop into a closed posi-

tion on the seat 22. By squeezing the bulb with the thumb 22 fingers of the other hand pressure is caused to exist within the bottle, filling device and the sack or reservoir of the pen. Air in the pen is compressed slightly and at the same time some ink flows by gravity into the pen. When the bulb is squeezed the ball offers resistance to the upward passage of air and ink from the bulb back into the bottle, thereby increasing the pressure in the pen and causing a little more ink to flow into the pen. Upon squeezing the bulb, the ball 20 eventually lifts and some air passes into the bottle from the rest of the system. Before gravity causes the ball to drop back when pressure on the bulb is withdrawn, some additional ink flows into the bulb from the bottle. The bulb assumes its normal shape on release, and in so doing creates a suction action in the pen, removing some air from the pen which is replaced by more ink flowing by gravity from the bulb into the pen.

In order to assure a proper balance of pressure, and primarily to avoid excessive back pressure of air in the bottle because of repeated manipulations of the bulb, the vent 25 heretofore mentioned will relieve such back pressure and maintain a proper working condition.

From the foregoing it will be understood the device when manipulated functions to deliver ink into the pen both on the compression of the bulb and by suction action of the bulb when the bulb is released. This enables a pen to be filled quickly and easily.

It is to be understood the invention is not restricted to the details above described, but includes all constructions and modifications coming within the scope of the appended claims.

I claim:

1. A device adapted to fill an article with fluid from a fluid container, said device consisting of a bulb having an inlet and an outlet, valve means

communicating with said inlet for controlling the flow of fluid between the container and the bulb when the device is attached to the container, means surrounding said valve means for attaching the device to the container in communication with the valve means, and means connected with the outlet to receive in a fluid-tight manner the article to be filled, said valve means comprising a tubular member whose inner end communicates with said inlet, a seat on said tubular member interiorly thereof at its inner end, a valve member freely movable in the tubular member between a closed position on said seat and an open position, means on the outer end of the tubular member to limit the opening movement of said valve member, said valve member being movable to open position by fluid pressure caused by compressing said bulb and movable by gravity to a closed position when the bulb is relieved of compression.

2. A device as set forth in claim 1, wherein said seat consists of a flange on the tubular member, said flange has a notch therein providing a vent, and said valve member is globular.
